United States Patent Office

Des. 175,835
Patented Oct. 18, 1955

175,835

REFRIGERATOR CONTAINER

Donald W. Hill, St. Louis, Mo.

Application August 25, 1952, Serial No. 21,183

Term of patent 14 years

(Cl. D44—1)

FIG-1-

FIG-2-

FIG-4-

FIG-3-

Fig. 1 is a side elevational view of a refrigerator container, showing my new design;

Fig. 2 is a top plan view thereof;

Fig. 3 is a bottom plan view thereof; and

Fig. 4 is a cross-sectional view taken along line 4—4 of Fig. 2.

I claim:

The ornamental design for a refrigerator container, substantially as shown.
